UNITED STATES PATENT OFFICE.

JOHN HOWARD FOOTE, OF BROOKLYN, NEW YORK, AND GEORGE S. KNAPP,
OF CHICAGO, ILLINOIS.

DESIGN FOR A DRUM-CASE.

SPECIFICATION forming part of Design No. 17,147, dated March 1, 1887.

Application filed March 20, 1885. Serial No. 159,618. Term of patent 3½ years.

To all whom it may concern:

Be it known that we, JOHN HOWARD FOOTE, of the city of Brooklyn, State of New York, and GEORGE S. KNAPP, of Chicago, Cook county, Illinois, have invented a certain new and Improved Design for Drum-Cases, of which the following is a specification.

Figure 1 represents a perspective view of our design as embodied in material form, the case being open; Fig. 2, a side elevation of the same, the case being closed; Fig. 3, a front elevation.

Our design embraces as the two essential portions the body A and cover B, which present jointly when closed the appearance of a short cylinder. The body portion embraces two flat circular parallel sides, a, jointed throughout one-half of their periphery by the intervening sheet or portion, b. An ornamental bead or binding, c, encircles the edges. A flat pocket, d, of the form shown, is located on the inner surface of one of the sides. The design for the top embraces the flat circular sides e and the intervening sheet, f, joined at its edges to the periphery of the

sides. An ornamental bead, g, encircles the peripheral portion, as shown. A handle, h, appears on the upper side of the top, and straps and buckles i or other fastening devices appear at the top and sides of the body. 30 Along one side of the top portion there is a pocket, k.

Having thus described our invention, what we claim is—

The design for a drum-case herein shown 35 and described, the same consisting of the circular ends a a, a semi-cylindrical portion, b, the semicircular ends e e, and the semi-cylindrical part f.

In testimony whereof we have hereunto set 40 our hands this 13th day of March, 1885.

J. HOWARD FOOTE.
